United States Patent Office

Des. 193,304
Patented July 31, 1962

193,304

TROPHY OR SIMILAR ARTICLE

Alexander M. Pistey, 87 Reservoir Ave.,
Bridgeport, Conn.

Filed Feb. 1, 1962, Ser. No. 68,610

Term of patent 7 years

(Cl. D29—23)

FIG. 3.FIG. 4.FIG. 5.

FIG. 1 is a front elevational view of a trophy or similar article, showing my new design;

FIG. 2 is a rear elevational view thereof;

FIG. 3 is a side elevational view thereof;

FIG. 4 is a vertical sectional view taken on the line 4—4 of FIG. 1; and

FIG. 5 is a horizontal sectional view taken on the line 5—5 of FIG. 1.

I claim:

The ornamental design for a trophy or similar article, substantially as shown.
